[57] **CLAIM**

The ornamental design for a cylindrical tube for packaging wireless communication devices, as shown and described.

DESCRIPTION

FIG. 1 is a front view of a cylindrical tube for packaging wireless communication devices;

FIG. 2 is a front view of the cylindrical tube for packaging wireless communication devices; and,

FIG. 3 is a top view of the cylindrical tube for packaging wireless communication devices showing a removable cap; the bottom plan view being a mirror image thereof;

The broken lines in FIG. 1 show environmental structure which is for illustrative purposes only and forms no part of the claimed design.

1 Claim, 2 Drawing Sheets

FIG. 1

FIG. 3

FIG. 2
